ROBERT E. DURNING,
INVENTOR

BY William A. Hirtle,

ATTORNEY.

UNITED STATES PATENT OFFICE.

ROBERT E. DURNING, OF AVALON, PENNSYLVANIA.

BOILER-COMPOUND HOLDER.

1,300,829.

Specification of Letters Patent. Patented Apr. 15, 1919.

Application filed August 12, 1918. Serial No. 249,589.

To all whom it may concern:

Be it known that I, ROBERT E. DURNING, a citizen of the United States of America, residing at Avalon, in the county of Allegheny and State of Pennsylvania, have invented certain new and useful Improvements in Boiler-Compound Holders, of which the following is a specification.

The present invention relates to an improved type of boiler compound holder, which is particularly applicable for use in steam boilers for dispensing the chemicals used to soften the water being used. The primary object of the invention is to provide a simplified device which is easily manipulated and adapted for use in connection with boilers of various sizes or for softening different quantities of water, which is durable, comparatively inexpensive in cost of production and maintenance, and efficient in furnishing to the water to be treated a uniform and regulated supply of material as required.

With these ends in view the invention consists in certain novel combinations and arrangements of parts as will be hereinafter more fully pointed out and set forth in the claims.

In the accompanying drawings I have illustrated the construction of the invention according to the best modes I have so far devised for the practical application of the principles of my invention.

Figure 1 of the drawings is a central vertical longitudinal section of my invention.

Fig. 2 is an end view of Fig. 1 taken from the right of same.

Fig. 3 is a cross-sectional view taken on line 3—3 of Fig. 1.

Fig. 4 is a detail view of a portion of the outer casing taken on line 4—4 of Fig. 2.

Fig. 5 is a side elevational view partly in section of a modified form of the device, showing an inner rack or crate designed to hold a number of receptacles containing chemicals.

Fig. 6 is a cross-sectional view of Fig. 5 taken on line 6—6 of Fig. 5.

Fig. 7 is an end view of Fig. 5 taken from the right of same.

Figs. 1 to 4 inclusive of the drawings show more particularly the preferred form of the device, and Figs. 5 to 7 inclusive a modified form of the same.

The numeral 1 indicates a preferably

cylindrical metallic tubular open-ended barrel designed to receive a number of inner receptacles 2 of similar cross-sectional form and adapted to contain a suitable boiler compound (not shown). The ends of the barrel 1 are closed by plugs or heads 3, which are provided with an annular inwardly turned flange 4 of proper size to fit neatly the inner peripheral face of the said barrel 1. Securing means for the heads is provided by means of thin metal strips 5 which are riveted to the inner wall of the barrel 1 at 6, and after the heads 3 are in place in the ends of the barrel, the strips 5 are bent over the said heads at 7, thus securely fastening them in position. It will be seen that the rivets 6 are placed in the barrel 1 at the proper points longitudinally so that the edges 8 of the flanges 4 just bear against the inner heads of the rivets 6, so that the latter form convenient "stops" for the heads 3. As shown in Fig. 3 the flanges 4 of the heads 3 have to be slightly flattened at 9 to pass over the strips 5, but as the latter are made of tin their thickness is negligible. Attention is called to the fact that the barrel 1 is made preferably of heavier metal such as steel or "wrought" pipe, while the heads 3, and metal strips 5, and the inner cylinders 2, are made of thin metal such as tin. In connection with the cheapness of production of the device it may be stated that the inner cylinders or receptacles 2 can be made of the ordinary "tin cans", or even second-hand or used tin cans can be used, and the heads which have been opened in use can be resoldered shut after having been loaded with the chemicals used for softening the water, thus making the cost for inner receptacles very small.

After the chemicals contained in the receptacles 2 have been dissolved and dissipated in a manner to be explained below, the outer barrel 1 can be reused by merely renewing the metallic strips 5, in case the latter have been injured at the point 7 by the bending which is necessary at this place.

Owing to certain ebullition movements of the water in the boiler (not shown), it has been found advisable to support the barrel 1 at an angle to the horizontal as shown in Fig. 1. For this purpose a metal band 10 which encircles the barrel 1 adjacent to one end thereof, has its free ends bent in diverging directions to form feet 11 for engagement with the bottom of the boiler. A bolt

12 clamps the band tightly around the barrel 1. If desired two such bands 10 can be used when it is necessary for the holder to be in a horizontal position, one such being placed near each end.

Each of the plugs or heads 3 is provided with perforations 13, one or more, at the right or elevated end of the barrel 1, and another (usually a single) perforation 14 at 10 the opposite or less elevated end of the barrel. The purpose of these perforations is to admit the water being softened by the chemical to enter the tube 1 at 14 and escape therefrom at 13, carrying with it the dissolved chemicals. Similarly each inner chemical containing receptacle 2 is provided with perforations 15, and 16 (see Fig. 3), corresponding to perforations 13 and 14 of the barrel 1, and for a similar purpose. It 15 will thus be seen that the water enters the barrel 1 at 14, thence entering each of the inner receptacles 2 at 16, loosens some of the chemicals within the same and carries them through the perforations 15 into the mixing 20 spaces 17 between and around the inner receptacles 2. In this connection it is noted that the receptacles 2 are maintained in spaced relation with respect to each other by means of the friction between the outer 25 surfaces of the said receptacles 2 and the interior surface of the barrel 1; and it is evident further that as sediment is deposited from the water of the boiler, between the receptacles 2 and within the barrel 1, the 30 spacing shapes or mixing chambers 17 are readily maintained between the ends of the receptacles. After being more completely dissolved and mixed for a short period in 35 these mixing spaces 17 within the barrel 1, the now thoroughly dissolved chemicals, and water are carried out through the perforations 13 in the end plug of the barrel into the boiler. The interior of the barrel 1, in this 40 way performs the function of a mixing chamber, where the chemicals are broken down into molecules which are more readily assimilated when they are later discharged into the boiler itself. It is noted in the drawings, that the interstices or spaces 17 45 between the ends of the adjacent inner receptacles 2, 2, etc., and also the space between the perimeter of the inner receptacles 2, and the inner circumference of the barrel 1, as clearly shown in the Fig. 3 of the drawings, have been made of considerable size 50 for the purpose of affording the necessary mixing space for the chemicals and water, prior to their discharge into the boiler itself. The amount of chemical being used can be 55 controlled by making as many perforations 15, and 13, etc., as is found necessary, but in practice it is found only one perforation at points 14, and 16 is necessary, while two or three at 15 and 13 give the best results, 60 for ordinary sized boilers.

In Figs. 5, 6 and 7 I have shown a rack or 65 crate 18, composed of four or more longitudinal strips of metal, 19, 24 of thin material 70 preferably, and secured by two or more metal bands 20 riveted to same as shown. At one end of the rack 18, the strips 19, 24 75 cross each other as shown dotted at 21 Fig. 7, while at the opposite end the strips are bent over as at 22, after the inner chemical receptacles 23 have been placed in the rack 75 in similar fashion to that described in connection with the barrel 1.

It will be seen that the charged rack 18 can be placed within the outer barrel 1, as 80 shown in Fig. 5, the purpose of the rack being for convenience in loading and shipping purposes. It will be understood that periodically the device has to be reloaded with inner receptacles 2 and 23 containing a fresh supply of chemicals, and the utility of such a 85 rack as 18 is at once appreciated.

It is also found that the sediment of 90 muddy waters will settle in the receptacles 2, and assist in clarifying same. This in itself is a minor matter but this feature adds 95 somewhat to the utility of the device as a whole.

I have a specially prepared boiler compound which I use in the holder in soluble form, and the boiler compound is dissolved 95 by the entrance and circulation of water in the interior of the holder, so that the solution passing through the perforations will permeate the water in which the device is contained as before explained, and soften or 100 otherwise prepare it for its desired use. Different sized holders containing a greater or lesser number, or diameter, of inner receptacles are used in connection with boilers of 105 different capacities, as may be necessary to keep the water impregnated for desired time periods without renewal of chemicals, as is readily appreciated.

The dispensation of the chemicals from 110 both the inner receptacles 2 into the chamber of the barrel at 17, and of the properly mixed chemicals and fluid from the barrel 115 into the boiler itself, may be accelerated or retarded according to the capacity of the boiler, or the time period in which it is desired to replenish the chemicals of the device, by making a greater or lesser number 120 of perforations in the ends of the inner receptacles, and the barrel. By the methods above described the device can be adapted 125 to suit the capacity of various boilers, and to carry a boiler of any certain size over any desired time period without replenishing the chemicals in the inner receptacles of the device. Time periods of a month or 125 more are common with my type of boiler compound holder, due to the side walls of the inner receptacles and the holder itself forming substantially closed compartments, thereby preventing the wasting away of the 130

chemicals, commonly occurring when holders having open sides and ends are used. With the latter type constant renewal of the chemicals is imperative, due to the latter not having protection from the direct action of the water, and the water currents within the boiler.

With my type of holder, the objections above delineated are overcome, and it is seen that I have provided a boiler compound holder of marked novelty and utility for the purpose specified.

What I claim is:—

1. A boiler compound holder comprising an open ended barrel, perforated plugs for closing said ends, and strips on said ends adapted to fold over and engage against said plugs for locking them in said ends.

2. A boiler compound holder comprising a barrel having closed side walls and open ends, a number of closed receptacles within the barrel, and having perforations in their opposite ends for controlling the flow of liquid therethrough, spaces between and around the inner receptacles within the barrel forming a mixing chamber, perforated plugs closing the ends of the barrel adapted to control the flow of the completely mixed chemicals and fluid through the barrel, and means for locking the said plugs in the ends of the same.

3. A boiler compound holder comprising an outer open ended barrel, a plurality of inner receptacles having closed side walls and ends, and perforations in opposite ends of the latter for controlling the flow of fluid and chemicals therethrough, perforated plugs closing the ends of the barrel adapted to regulate the passage of mixed chemicals and fluid through the latter, a number of metal strips riveted to the end walls of the

barrel adapted to fold over the end plugs and form locking means therefor.

4. In a boiler compound holder having an open ended barrel, perforated plugs of lighter weight material having inwardly turned flanges engaging against the inner end walls of the barrel, a number of metal strips riveted to the walls of the barrel, said rivets forming a stop for the inner edges of the plug flanges and the metal strips folded over the ends of the said plugs to hold same in position.

5. In a boiler compound holder having an open ended barrel, perforated plugs of lighter weight material having inwardly turned flanges engaging against the inner end walls of the barrel, a number of closed inner chemical containing receptacles provided with flow control means, a number of metal strips riveted to the walls of the barrel, said rivets forming a stop for the inner edges of the plug flanges, and the metal strips folded over the ends of the plugs to hold same in position.

6. In a boiler compound holder, an open ended barrel having closed side walls, a number of closed inner chemical holding receptacles in spaced relation with respect to each other, and each provided with means for controlling the flow of liquid therethrough, a rack for holding a series of inner receptacles, slidably entering the barrel, and plugs closing the ends of the barrel provided with means for controlling the flow of fluid through the latter.

In testimony whereof I affix my signature in the presence of two witnesses.

ROBERT E. DURNING.
